UNITED STATES PATENT OFFICE.

ISIDOR DREYFUSS, OF NEW YORK, N. Y.

TAPE-APPLYING MACHINE.

No. 867,807.

Specification of Letters Patent.

Patented Oct. 8, 1907.

Application filed September 11, 1906. Serial No. 334,159.

To all whom it may concern:

Be it known that I, ISIDOR DREYFUSS, a citizen of the United States, and a resident of the city of New York, borough of Manhattan, in the county and State of New York, have invented a new and Improved Tape-Applying Machine, of which the following is a full, clear, and exact description.

The purpose of the invention is to provide a machine especially adapted for inserting tape into paper boxes, or penetrable boxes of a kindred type, which tape may be employed for holding the contents of the boxes in place, or for holding one or more sections in position.

A further purpose of the invention is to so construct a machine of the character described that it will be comparatively simple, durable and economic and practically automatic in action, and so that the tape will be drawn from a suitably placed reel, gripped by a needle and carried down thereby to and through the box adapted to receive it and said tape cut the desired length.

A further purpose of the invention is to provide a means for holding the tape in position to be cut after it has been passed through the box if desired, or whereby the tape can be cut before it has been introduced into the box, and the free end of the tape be prevented from becoming entangled with the needle.

Another purpose of the invention is to provide mechanism whereby the tape will be unreeled, conducted to and through the box and cut the desired length during one continuous movement of the master parts of the machine, or whereby the unreeling of the tape, its conducting to and through the box and the temporary retention of the end passed through the box can be accomplished during the downward movement of the master parts, for example, and the cutting of the tape be performed while said tape is taut and at the upward movement of the master parts.

The invention consists in the novel construction and combination of the several parts, as will be hereinafter fully set forth and pointed out in the claims.

Reference is to be had to the accompanying drawings forming a part of this specification, in which similar characters of reference indicate corresponding parts in all the figures.

Figure 1 is a side elevation of the machine; Fig. 2 is a sectional side elevation of the upper portion of the machine; Fig. 3 is a front elevation of that portion of the machine shown in Fig. 2; Fig. 4 is an enlarged transverse section taken practically on the line 4—4 of Fig. 3, illustrating the manner in which the cutter shaft is actuated; Fig. 5 is an enlarged transverse section taken practically on the line 5—5 of Fig. 3, illustrating the construction of the cutting mechanism, the shear blades of which are shown open to receive the tape; Fig. 6 is a sectional side elevation of the parts shown in Figs. 2 and 3, illustrating the tape carried down to enter a box and the cutting

mechanism being about to act; Fig. 7 is a view similar to that shown in Fig. 5, but illustrating the position of the parts of the cutting mechanism when its shear blades are closed; Fig. 8 is an enlarged detail view of the detent mechanism for the tape, which acts to prevent the upward movement of the body of the tape after the desired length has been cut therefrom, and which holds the tape in position to be again engaged by the needle; Fig. 9 is a transverse section taken practically on the line 9—9 of Fig. 8; Fig. 10 is a front elevation of a slightly modified form of the machine; Fig. 11 is a side elevation of the machine shown in Fig. 10; Fig. 12 is a horizontal section taken practically on the line 12—12 of Fig. 11, drawn upon an enlarged scale; Fig. 13 is an enlarged sectional side elevation of the upper portion of the machine; Fig. 14 is a sectional side elevation of parts shown in Fig. 13, drawn upon a larger scale; Fig. 15 is a horizontal section taken practically on the line 15—15 of Fig. 14, showing the cutter in plan view and the shear blades open; Fig. 16 is a detail sectional view through the rest for the box and the mechanism employed for holding the end of the tape passed through the box prior to the action of the shears on said tape; Fig. 17 is a front elevation of the needle and needle-carrying mechanism; and Fig. 18 is a section taken practically on the line 18—18 of Fig. 14, through the detent mechanism employed to prevent the tape riding back to the reel in the form of the machine shown in Fig. 10.

The main frame of the machine is a stationary frame and consists of an upper preferably rectangular section A and an intermediate correspondingly-shaped section A', together with supports for said sections. The upper frame section A consists of front and rear bars 10 and side bars 11, and the intermediate or lower section A' consists of front and rear bars 10^a and side bars 11^a, the front bar being provided with a longitudinal slot 10^b extending from end to end.

Rear uprights 12 and forward uprights 13 are passed through suitable eyes 14 formed in the sections A and A', being secured to said sections, and said standards 12 and 13 are circular in cross section and are connected to the floor or other support in any suitable or approved manner.

The sections A and A' extend some distance beyond the forward standards 13 as is shown in Fig. 1.

As is shown in Figs. 1 and 10 a drive shaft 15 is mounted to turn in suitable bearings 16 adjacent to the bottom of the said main frame, said bearings extending from the front to the rear standards as is particularly shown in Fig. 1, and said shaft 15 is extended beyond one bearing 16 and provided with a pinion 17 and a driving pulley 18 that are secured thereon. In addition to the shaft 15 to which the power is applied a main driving shaft 19 is employed, parallel with and below the shaft 15. The main drive shaft 19 is journaled in bearings 20, located below the bearings 16, and

the main shaft 19 extends beyond the frame at the same end as does the drive shaft 15. A gear wheel 21 is loosely mounted on the projecting end of the main shaft 19, and the hub of said gear wheel 21 is provided with a 5 clutch face 21^a, adapted for engagement with a clutch 22, usually an ordinary pin clutch, which is mounted to slide upon and turn with the shaft 19 and to engage with the clutch face 21^a of the gear wheel 21.

The pin clutch 22 is provided with the usual spring 10 23, which forces it in engagement with the clutch face 21^a of the gear wheel 21, and the pin 24 of the clutch is spring actuated and the springs bear upon a support 25. The pin 24 is operated through the medium of an arm 26 connected with the said pin and attached to a treadle 15 27 suitably pivoted at the lower portion of the main frame, which treadle at its forward end, or the end to be engaged by the foot, is held elevated by means of a spring 28. Two or more devices for placing tape in a box may be mounted upon the above described main 20 frame. The devices are alike in construction and therefore but one of them will be described.

A main guide bar 31 rectangular in cross section is secured at its upper end to a block 32, which is held to slide on the front bar 10 of the upper section A of the 25 main frame, and the lower end of this main guide bar 31 is secured to a block 33 provided with a tongue which travels in the slot 10^b in the front bar of the lower frame section A'. The lower block 33 is held in adjusted position by means of a suitable set screw 33^b passed through 30 the front bar 10^a from the back as is shown in Fig. 2, and the said lower sliding block 33 is provided with a forward horizontal extension 33^c, in which extension a vertical opening 35 is made for the downward passage of the tape and likewise for the reception of an upwardly-extending and vertical tongue 34 held in place by means of a screw 36, or its equivalent. The object of this tongue is to receive the upper free end of the tape after the tape is cut, preventing said free end from becoming entangled with that end engaged by the 40 needle to be hereinafter described and which is to be introduced into the box.

A carriage is provided adapted to carry the tape-conducting mechanism, which carriage consists primarily of two guide sleeves 37, which are mounted to slide 45 upon the forward standards 12, and each of said guide sleeves 37 is provided with an eye 38 at its front, through which eye an operating shaft 39 is passed. This shaft is actuated by crank arms 40 secured to its ends outside of the main frame, the outer ends of said 50 crank arms being pivotally connected with links 41, which links in their turn are secured to the end portions of a shaft 42 journaled in bearings 42^a secured to the rear uprights 12 of the said main frame as is shown in Fig. 1. One of the links 41 is pivotally connected with 55 a pitman 29, and said pitman extends down to the lower portion of the machine at one side and is pivotally connected with a crank arm 30 on the main shaft 19 of the machine, as is shown in Figs. 1 and 10.

In the further construction of the aforesaid carriage 60 a slide 45 is mounted upon the main guide bar 31, as is best shown in Fig. 2. This slide is provided at its rear with horizontal parallel projections 46 and 47, between which the operating shaft 39 passes, and said shaft is held in position between these two projections 65 by means of a set screw 48 or its equivalent. In order

to take up any lost motion, or to provide for any wear between said slide 45 and the main guide bar 31, a plate 49 is located within the slide between its rear section and the rear face of the bar as is also shown in Fig. 1; and the said plate 49 is held adjusted to the said bar by 70 means of suitable screws 49^a.

A needle bar 50 also preferably rectangular in cross section, is either attached to or constitutes an integral portion of the front of the slide 45, extending downward therefrom parallel with the front face of the main guide 75 bar 31. The lower end of the said needle bar 50 at its rear face is beveled as is shown at 50^a in Fig. 2, and a needle 51 is secured to the lower end of the said bar 50 at its front face, extending below the lower end of the bar. The needle 51 is in the form of a flat strip of 80 metal provided with a series of teeth at its lower end. These teeth are adapted to engage with the tape as will be hereinafter described and to carry it down and pass said tape through the box to which it is to be applied, usually at the lower corner portions of the box. At one 85 side of the slide 45 a diagonal or cam groove 52 is produced as is shown in Figs. 1 and 7, which cam groove or surface 52 is adapted to operate the cutting mechanism in a manner to be hereinafter particularly set forth.

A carriage constructed as has been described is counterbalanced by means of a weight 53 and said weight may be made to travel in vertical guideways 55, extending down from the top section A of the main frame if so desired. Cords or cables 54 are attached to said weight 53, which cords or cables are carried up over 90 pulleys 56 as shown in Fig. 1, said pulleys being secured to a shaft 57 mounted to turn in the said upper section A of the main frame, and the other ends of the said cords or cables 54 are carried downward at the front and are attached to the operating shaft 39 by 95 means of suitable eyes 58 formed thereon, or by equivalent means as is illustrated in Fig. 10.

As shown in Fig. 2, on the upper end of the main guide bar 31 a collar 59 is secured by means of a set screw 59^a or its equivalent; and at the left hand side of 105 the said collar 59 the upper end of a supporting bar 60 is secured, which supporting bar at its lower end is provided with a forwardly extending table 61 adapted as a support for the cutting mechanism for the tape, to be hereinafter specifically described. At the upper end 110 portion of the said supporting bar 60, which bar extends down parallel with the main guide bar 31, a horizontal bearing arm 62 is provided, extending preferably in direction of the left hand side of the machine as shown in Fig. 3. In this arm 62 the upper end portion 115 of a cutter-controlling shaft 63 is mounted to turn, said shaft being likewise mounted in the upper sliding block 32. The lower end of the shaft 63 is mounted to turn in the lower sliding block 33 carried by the main guide bar 31.

A sleeve 64 is secured to the upper end portion of the cutter-controlling shaft 63 between the block 32 and the bearing 62, the attachment being preferably made by means of a set screw 64^a as is shown in Fig. 4; and in the peripheral surface of the said sleeve 64 a recess 65 125 is made as also indicated in Fig. 4. This sleeve 64, as will be hereinafter described, is adapted to operate a cutter actuating shaft 70, which is parallel with the shaft 63 but in front of it.

A second sleeve 66 is adjustable upon the said cutter- 130

controlling shaft 63, being slidably mounted thereon and capable of movement to almost the upper end of the shaft and practically to its lower end. This adjustable sleeve 66 as is best shown in Figs. 6 and 7, is held 5 in adjusted position on its shaft by a set screw 67 or a like device, and is provided with a key 68 adapted to slide in a groove in the said shaft. Said adjustable sleeve 66 is further provided at its peripheral surface with a pin 69. This pin is adapted to enter the cam 10 slot 52 at the side of the slide 45 at the upward and downward movement of said slide, and at the downward movement of said slide the sleeve 66 is moved out of normal position, thus rocking the shaft 63 in one direction; and as the slide 45 moves upward it restores 15 the sleeve 66 to its normal position and likewise the shaft 63. This movement of the shaft 63 is adapted to impart a closing action on the part of the shears or cutters employed at the downward movement of the slide, and an opening action at the upward movement of the 20 slide.

The cutter-actuating shaft 70 above referred to is journaled at its upper end in the bearing arm 62 of the supporting bar 60 and is provided with a sleeve 71 secured thereto above the bearing arm by means of a set 25 screw 72. Said sleeve 71 carries a single tooth 73, which tooth enters the recess 65 in the fixed sleeve 64 of the cutter-controlling shaft 63, as is shown in Fig. 4. Thus it will be observed as the cutter-controlling shaft 63 is rocked by the upward and downward movements of the 30 slide 45 a similar rocking movement is imparted thereby to the cutter-operating shaft 70. A collar 74 is secured to the cutter-actuating shaft 70 below the bearing arm 62 and serves to prevent said shaft 70 from shifting upward; and the lower end of said shaft 70 is mounted 35 to turn in or upon the table 61 at the lower end of the said supporting bar 60. The cutting mechanism B above referred to is best shown in Figs. 5 and 7. In Fig. 5 the blades of the shears are shown open to receive the tape, and in Fig. 7 they are shown closed, having 40 severed the tape.

A crank arm 75 is secured to the lower end portion of the cutter-actuating shaft 70, and above said crank arm a collar 76 is usually secured to prevent the arm from rising upward, while at the outer end of said crank arm 75, 45 which extends forwardly over the table 61, two links are pivotally connected, preferably of the same length, namely an upper link 76^a and a lower link 77.

A projection 78 is made from the forward end of the table 61 adjacent to its right-hand side edge, and 50 through said projection the pivot 81 for shear blades 79 and 80 is passed, which pivot pin is provided with an upper head 82 as shown in Fig. 6; and a spring 83 is coiled around the pivot pin at that portion which extends through and beyond the table. Nuts 84 are 55 screwed upon the lower end of the said pivot pin 81 so as to regulate the tension of said pin on said shear blades 79 and 80. The upper link 76^a connected with the crank arm 75 is pivotally connected to an extension 85 from the outer end of the left-hand shear blade 60 80, the extension being located near the inner or free end of said blade, and the opposing link 77 is pivotally connected with an extension arm 86 from the pivot portion of the right-hand shear blade 79. The shear blades face an opening 61^a in the table 61, through 65 which the main guide bar 31 passes and the needle 56,

and through which the tape 96 carried by the needle of the needle bar likewise passes, and the directing plate 34 is visible at the forward portion of this opening as is shown in both Figs. 5 and 7.

A vertical tension bar 87 is about centrally fulcrumed upon a forwardly-extending bracket 88 secured to the front portion of the supporting bar 60, as is shown in Figs. 2 and 3, and said tension bar extends downward at the front of the needle bar. Further, the said supporting bar 60 is provided with a guide projection 89 from its right-hand side, which serves to direct the lower portion of the tension bar 87 in its rocking movement.

A forwardly-extending arm 89^a constitutes an integral portion of the upper end of the tension bar 87, and 70 a spring 90 is secured to the outer end of the said arm 89^a and to the front of the fixed sleeve 59 on the main guide bar 31, which spring 90 tends to draw the upper end of the tension bar rearward or in direction of the main guide bar, and when the said spring 90 so acts the 75 lower end of the tension bar is carried away from the needle-carrying end of the needle bar 50. The tension bar 87 is of sufficient length to extend somewhat below the needle 51 when the needle bar is in its upper or normal position as is shown in Fig. 2, and preferably 80 while the upper portion of the tension bar is straight its lower portion, or that portion below its pivot is 85 more or less inclined toward the rear.

The lower portion of the tension bar 87 is L-shaped in cross section, comprising a member *a* which is at right angles to the needle bar 50 and which is the main member of the said tension bar, and a member *a'* which is opposite to and parallel with the front face of the needle-carrying bar 50, as is shown in Figs. 2 and 3. At the upper end portion of the said tension bar 87 what I 90 term a track bar 91 is adjustably secured, and the upper portion of this track bar is inclined upward and rearward so as to extend beyond the rear edge of the upper end portion of the said tension bar as is shown in Figs. 2 and 6. When the carriage for the needle bar 100 is in its upper or normal position shown in Fig. 2, the track bar will be in engagement with the front face of the slide 45 and its upper end will therefore be forced outward, the spring 90 will be placed under tension and the lower end of the said tension bar will be carried 105 inward as far as is desirable in direction of the needle 51 to facilitate the needle taking the tape 96, which tape is held at the bottom edge of the tension bar; but when the carriage is in its lower position as is shown in Fig. 6, the spring 90 draws the upper end of the tension bar 87 rearward and carries the lower end of said tension bar out or away from the needle end of the needle-carrying bar, thus preventing any undue friction when the needle engages the tape to carry it downward and 110 secure it in the box.

What I term a directing plate 92 is adjustably pivoted at its upper end on the front face of the member *a'* of the tension bar 87, as shown particularly in Fig. 8. This directing plate extends down to the lower edge of the tension bar, and in its inner longitudinal edge near its bottom is provided with a recess 93, and at its bottom with a foot 94 that extends in direction of the main member *a* of the said tension bar. The foot 94 is provided with an outwardly-extending toe 95 parallel with yet spaced from the main member *a* of said ten- 115 120 125 130

sion bar 87, as is shown in Fig. 9. The tape 96 is carried down in engagement with the front face of the member *a'* of the tension bar and in engagement with the adjacent face of the member *a* as is shown by broken lines in Fig. 8, and between the toe 95 of the directing plate and the member *a* of the tension bar. Thus it will be observed the tape is guided as it passes from the tension bar, and by means of the adjustment of the directing plate 92 tape of different widths may 10 be adapted to the machine.

What I denominate a combined tension and detent plate 97 is employed, which plate is incidentally used to impart more or less tension to the tape in a downward direction, but primarily is adapted to prevent the 15 tape moving upward at its severed end after it has been cut by the shear blades described. This plate 97 is pivoted to the member *a* of the tension bar 87 by means of a suitable pin 98, and at the lower end of said plate a series of pointed fingers 99 is secured, preferably of a 20 spring material. Said fingers 99 engage with the member *a* of the tension bar 87 opposite the recessed portion of the directing plate 92. The said tension and detent plate 97 is held to its work by means of a spring 100, secured to the tension bar and having bearing 25 upon the front face of the said plate 97, as is shown in Figs. 2, 6 and 8.

The tape 96 is unwound from a reel 101 mounted to turn upon an upright post 102 secured to the outer end of a forwardly-extending pocket 103, connected with 30 the supporting bar 60; and at the rear of the reel-carrying post 102 parallel and spaced guide posts 105 are located, connected by a cross bar 104 over which the tape 96 passes downward along the tension bar 87 through a suitable guide 106, and then between the 35 tension bar and the tension and detent plate 97 and directing plate 92 out beyond the lower end of the said tension bar as has been described.

A directing member 107 is employed to direct the 40 cut ends of the tape 96 to the rear, holding said tape in such position that it will be readily engaged by the needle 51 as the needle bar 50 descends. This directing member consists of a substantially L-shaped plate pivoted at its upper end to the member *a* of the tension bar, and its lower end 108 extends below the lower 45 edge of the tension bar 87, and the rear extremity of this member 108 is more or less downwardly curved, as shown in Figs. 2 and 6. After the shears have cut the tape the lower member 108 holds the cut portion of the tape against the bottom edge of the tension bar 50 87 thus causing the lower extremity of the tape to assume a substantially horizontal position in the path of the needle.

The rearward or holding portion of the said directing member 107 is controlled by a stop 109, which engages 55 with the forward edge of the tension bar 87, and said stop may be adjustable. The directing member 107 is held to its work by a spring 110 secured to the tension bar 87 and engaging with the front face of the said member, as is shown in Figs. 2 and 6. When the needle 60 engages with the tape to carry it downward, the slide 45 will have passed the track bar 91 on the tension bar 87, and the spring 90 will then act to draw back the top of the tension bar and carry its lower end forward, thus taking the directing member out of the 65 path of the descending needle; and since said directing

member is pivoted, as the tape is placed under tension by its engagement with the needle, the directing member is pushed forward out of the way, thus relieving the tape from undue tension.

A table 111 is provided for the boxes into which the 70 tape is to be introduced, and this table is secured to a front cross bar 112, adjustably attached to the forward uprights or standards 13. The table is provided upon its upper face with a V-shaped trough 113, having an opening 114 in its bottom or where its members 75 connect, which opening registers with a corresponding opening in the table 111, and the opening in said table 111 is usually surrounded by a suitable housing 115, into which the needle carries the tape after forcing said tape through the box. The box is placed cornerwise 80 in its trough support 113, as is shown in Fig. 1, since it is customary to pass the tape through the bottom corner portions of the box.

In the operating of this type of machine, the parts being in their normal position shown by Fig. 1, the 85 treadle 27 is pressed downward, which brings the clutch into action to produce one revolution of the main shaft 19, and during such revolution the carriage is carried downward and then upward to its normal position. As the carriage is moved downward through its 90 connection with said shaft 19, the needle bar descends with the carriage, the needle grips the supported lower end of the tape and carries said tape downward forcing the directing member forward out of the way; and as soon as the needle has passed the open shear blades 79 95 and 80 as far as has been determined by the set of the adjusting collar 66, the projection 69 from that collar will enter the cam groove 52 in the slide 45, and the cutter-controlling shaft 63 will be rocked, imparting a similar motion to the cutter-actuating shaft 70, the direction of rotation being such as to close the shear blades and sever the tape as shown in Fig. 7. The needle continues downward, and the upper end portion of the severed strand of tape will drop over the directing plate 34 while the needle carries the other 105 end of the tape through the bottom of the box, where the tape is held by frictional contact with the material of the box, enabling the needle to be readily withdrawn for the upward movement of the carriage. In the meantime the severed end of the tape from the reel 110 101 is prevented from riding up by the action of the combined tension and detent plate 97; and as the carriage ascends the pin 69 on the adjusting sleeve 66 of the cutter-controlling shaft 63 again enters the cam groove 52 of the slide 45, and the shafts 63 and 70 are 115 returned to their normal positions, which action causes the shear blades 79 and 80 to open. When the slide 45 reaches its upper or normal position the clutch will have ceased to act on the shaft 19 and the movement of the carriage will have stopped and the track bar 91 120 will have engaged with the said slide 45 and thus forced the lower end of the tension bar 87 rearward, bringing the cut end of the tape in position to be engaged by the needle 50 when the carriage is again sent downward.

In the form of the machine shown in Fig. 10 and the following figures of the drawings the needle-carrying and knife-operating sections differ slightly from that shown in the other views to the extent that in this form of the device the tape is first carried down through 130

box and is held where introduced and is cut while the needle-operating mechanism is at rest on its upward stroke; and as the operating bar for said mechanism travels further upward; whereas, in the other form of the machine the entire operation of inserting and cutting is performed at the downward stroke of the needle-operating mechanism.

The main frame and the motive power are identical, together with the carriage, except that the slide 45 is dispensed with; and further, in connection with the frame the upper and lower sliding blocks 32 and 33 are employed as in the other form, connected by the main slide bar 31; and in this type of the machine any desired number of special devices to be hereinafter described may be mounted upon the one main frame.

The carriage differs slightly in construction in this type of the machine, in that the operating shaft 39 is provided at its front surface with a longitudinal groove 110^a as is shown in Figs. 10 and 13. A standard 112^a, 20 circular in cross section, is secured at its upper end in any suitable or approved manner to the head block 111^a which is mounted to slide on the main guide bar 31 and is held in adjusted position by a set screw or its equivalent. The lower end of this cylindrical standard 112^a 25 is reduced in diameter as shown at 112^b in Fig. 14; and said cylindrical standard 112^a is adapted as a guide for a knife-operating tube 113^a, which has limited sliding movement on said standard. The movement of the knife-operating tube 113^a is limited by passing a stop 30 pin 114^a out through a slot 115^a made longitudinally in preferably the forward face of said knife-operating tube. The knife-operating tube 113^a is cut away at the rear portion of its lower end and at the side, being therefore more or less tapering at said lower end; and in the lower 35 or tapering portion of said knife-operating tube 113^a, which is the front portion of said tube, two slots 116 and 117 are produced, which slots converge at their lower ends and diverge at their upper ends. The knife-operating tube 113^a is held in its normal position by a spring 40 118, attached to the forward upper portion of said tube and to the upper front portion of the guide standard 112^a for the tube, as clearly shown in Figs. 10 and 13.

When the knife-operating tube 113^a is in its normal position, the contracted lower end of said tube will extend but a slight distance beyond the lower end of the 45 guide standard 112^a, as is shown in Fig. 14.

Two shear blades 120 and 121 are employed to cut the tape, and each blade is provided with an eye 122 preferably at its forward end, and the eye sections of the 50 blades are mounted one upon the other and the reduced lower end 112^b of the guide standard 112^a is loosely passed through the eyes 122 of said shear blades as is illustrated in Figs. 14 and 15. A washer 123 is carried by the reduced lower end 112^b of the guide standard 55 112^a as is likewise a coiled spring 124 and nuts 125 as is shown in Fig. 14. These parts serve to hold the eye sections of the shear blades in suitable frictional contact. A pin is projected from the eye section of each of the shear blades 120 and 121, said pins for the 60 blades being designated respectively as 120^a and 121^a. The pin 121^a for the blade 121 passes through the slot 116 in the knife-operating tube 113^a, while the pin 120^a for the opposing blade 120 passes out through the slot 117 in the said knife-operating tube, as is clearly shown in 65 Fig. 1.

When the knife-operating tube 113^a is in its upper or normal position, the pins 121^a and 120^a of the shear blades will be at the lower end portions of the slots 116 and 117, and consequently the shear blades will be held open, as shown in Fig. 15. When, however, the knife-operating tube 113^a is forced downward the pins 121^a on the shear blades will ride up in the slots 116 and 117, causing the said shear blades to close and sever the tape which may be between them.

The operating mechanism for the knife-operating tube 113^a is as follows, and is best shown in Fig. 13;—A hanger 126 is secured to preferably the left-hand side of the head block 111^a, extending down below said block, and said hanger is provided with a forwardly-extending horizontal arm 127, which carries a 80 forwardly-extending adjustable stop pin 128. A lever 129 is pivoted at the lower end of the hanger 126; and at the rear end of the said lever an upwardly-extending arm 130 is secured. To the arm 130 a downwardly-extending finger 131 is pivoted, pressed rearward by means of a spring 132 located between it and said arm 130; but the outward or rearward movement of the finger 131 is controlled by a check rod 132^a. This rod 132^a is so adjusted that while it is free to slide in the arm 130 it will hold the lower end portion of the 90 finger 131 in a position to be engaged by the slotted portion 110^a of the operating shaft 39 when the carriage ascends, as is also shown in Fig. 13. At such time the shaft 39 in its upward movement by such engagement will raise the rear end of the lever 129 95 and will depress its forward end 129, which end carries with it an adjustable strap 130^a, pivotally connected with a bar 133, said bar being likewise pivotally connected with the upper end of the knife or shear-operating tube 113^a, as is shown in Fig. 13. 100 Thus it will be observed that as the forward end of the lever 129 is pressed downward, it carries downward with it the said shear or knife-operating tube 113^a causing the shear blades to close; and as soon as the finger 131 is released from the operating shaft 39 the 105 spring 118 will act to immediately restore the knife or shear-operating tube 113^a to its normal position, thus opening the shear blades. When the operating shaft 39 descends for purposes to be hereinafter described, it simply pushes the finger 131 inward or forward and 110 has no action at such time on the lever 129. The connecting rod 133 is preferably made in adjustable sections so as to control the movement of the knife or shear-operating tube 113^a.

The needle bar 134 is secured to the forward portion of a slide 135 corresponding to the slide 45 in the other construction. Said slide 135 is usually of skeleton construction, embracing a vertical rear member and upper and lower horizontal members which are mounted to slide on the main guide bar 31, and to 120 which horizontal members the needle bar 134 is secured, as is also best shown in Fig. 13. This slide 135 is provided with a rearwardly-extending lug 136, integral with or attached to its rear vertical member, and said lug 136 is adapted to be engaged by the operating shaft 39 on its downward movement, at which time said shaft carries said slide 135 with it, and consequently the needle bar 134. 125

A tubular shield 137 is provided for the lower end of the needle bar 134 as is shown in Figs. 13 and 14. 130

- This tubular shield has its rear lower portion downwardly and forwardly beveled, as shown at 138 in said Figs. 13 and 14, and at its lower forward portion an opening 139 is produced, extending to its lower edge.
- 5 When the needle bar shield 137 is in normal position its lower end protects the needle 140 which is secured to the lower end of the needle bar; and this needle, as is shown in Fig. 17 preferably consists of a flat body section provided with a series of teeth at its lower end.
- 10 At the upper end of the needle bar shield 137 a collar 141 is produced, and a spring 142 holds said needle bar shield in its normal position shown in Fig. 14, said spring being secured at its upper end to the upper portion of the shield, and at its lower end is attached
- 15 by means of a hook 143 or its equivalent to the needle bar 134, said hook passing through a longitudinal slot 144 in the rear face of the said shield as is also shown in Fig. 14. In this manner the movement of the shield is limited.
- 20 The needle bar 134, its slide 135 and all the parts carried by said needle bar and its shield are slightly more than counterbalanced by a tension device which tends to return the needle bar to its normal position after having been forced downward by the operating
- 25 shaft 39 and released therefrom. Said tension mechanism consists of a chain or cable 145 which is passed around a drum 146 mounted upon a shaft 147 carried by a bracket 148 secured to the upper portion 32 of the main guide bar 31, and barrel springs 147^a are
- 30 mounted on the shaft 147, and act to cause the cable to be wound upon said drum, said springs being placed under tension when the needle bar is carried downward, acting to return the needle bar to normal position when released from downward pressure.
- 35 A bracket 149 is shown attached to the upper portion of the head block 111^a and as extending forwardly therefrom, and said bracket is provided with a post 150 upon which the reel of tape 151 is loosely mounted. The tape is passed over a friction roller 152 located
- 40 between vertical guides 153 also supported by a bracket 149, and supplemental guides may be employed if desired. The tape 151 after being passed over the friction roller 152 is carried down through the guide opening 164 in the forward portion of the head block 111^a
- 45 but to the rear of the guide standard 112^a for the shear-operating tube 113^a, as best shown in Fig. 13; and as is illustrated in Fig. 14 the tape is further passed through a guide opening 155 in the collar 141 at the top of the needle bar shield 137, thence down to the lower portion
- 50 of the said shield through the lower guide 156 also carried by the shield. A detent and feed mechanism, however, is employed to prevent the upward movement of the tape after it has been cut, or as it is being drawn down and primarily to feed the tape downward.
- 55 This mechanism consists of an arm 157 pivoted at its upper end between ears 158 secured to the forward face of the needle bar shield 137 near its upper end, and at about the central portion of said arm a series of downwardly-inclined blades or needles 159 are secured, ex-
- 60 tending through the rear face of said arm as is shown, in Figs. 14 and 18. The said needles 159 are normally held in engagement with the tape, which passes immediately to the rear of said arm, by means of a spring 160, having bearing upon the front face of said arm as
- 65 is particularly shown in Fig. 14. In order that the

tape shall be properly guided where the detent needles are located, and furthermore in order that the arm 157 shall not be pressed too far to the rear and thus pierce the tape and retard it in its downward movement, opposing guide lugs 161, best shown in Fig. 18, extend 70 horizontally from the needle bar shield in a forward direction below the ears 57, and the spring 160 causes the inner or rear face of the arm 157 to have bearing against said lugs.

A swinging guide arm 162 is provided for the lower 75 forward portion of the needle bar shield 137. Said swinging guide arm 162 is best shown in Figs. 14 and 17. It is of angular construction, having a downwardly and rearwardly inclined lower member 163 which extends through the front lower slot 139 in the needle bar guide 80 normally to a point below the carrying needle 140 on said bar and in the path of said needle as is shown in Fig. 14. An opening 164 is produced in the swinging guide arm 162 where its two members connect, and the front face of the body portion of the said swinging arm 162 above said opening 164, is curved downward in direction of said opening. A guide plate 165 secured to the rear face of the swinging guide arm 162 extends downward and forward through the opening 164 in said swinging guide arm, and said guide plate 165 at its outwardly-extending end is likewise apertured, the aperture therein being in alignment with the opening 164 in the swinging guide arm and the cut-away portion 139 of the needle bar shield 137.

A spring 164^a serves to normally hold the swinging 95 guide arm 162 quite close to the forward lower face of the needle bar shield, as is shown in Fig. 16. The tape 151 after having been passed through the lower guide 156 is carried down to an engagement with the forward face of the body of the swinging guide arm 162 100 and is then carried through the opening in the outer end of the guide plate 165, also through the opening 164 in said swinging guide arm and through the opening 139 at the forward bottom portion of the needle bar shield to an engagement with the upper face of the 105 lower member 163^a of the said swinging guide arm, thus holding the lower end of the tape in the path of the needle 140; and as the needle bar descends and the needle 140 takes hold of the tape, the swinging guide arm 162 is pushed to the rear out of the way by the 110 needle in its descent. Therefore, while the tape is guided at the lower end of the needle bar shield in operation it is not subjected to any undue tension.

A lug 166 extends horizontally forward from the lower slide 33 of the main guide bar 31, which lug engages the collar 141 on the needle bar guide when said needle bar guide has reached its desired lowest point, thus holding said needle bar shield stationary at such time while the needle bar travels further on to deposit the tape in the box.

115 At a suitable distance below the lower frame section A', a cross bar 167 is secured to the front uprights or rods 13 of the frame as particularly shown in Figs. 10 and 12, and upon this cross bar horizontal tables 168 are mounted to slide, one table for each device carried 120 by the main frame. Upon said tables the boxes designated as 168^a are adapted to rest as is shown in Fig. 1C when the tape is to be inserted therein. A table 168 is provided with a longitudinal slot 169 at the central portion of its outer end and with a channeled down- 130

ward extension 170 at its rear portion, through which extension a cross bar 167 loosely passes, being held in adjustable position by a set screw 171.

A channel 169^a is produced in each side wall of the 5 slot 169, and at the outer end of said slot 169 a jaw 172 is fixedly yet removably secured, while an opposing jaw 173 is mounted to slide in said channels 169^a to and from the fixed jaw. A rod 174 is secured to the sliding jaw 173 as is shown in Fig. 16, which rod passes loosely 10 out through the rear end of the table 168 and the rear end of said bar is threaded. A spring 175 is coiled around the rod 174 within the slot 169, and said spring tends to keep the sliding jaw 173 in biting engagement with the fixed jaw 172.

15 A bracket 176 extends down through the side of the table 168 at the rear, and upon said bracket a trip lever 177 is fulcrumed, the upper end 178 whereof is forked to receive the rear end of the rod 174, being prevented from sliding off the rod by nuts 179 screwed upon the 20 rear threaded extremity of the rod as is shown in Fig. 16.

The lower end of the trip lever 177 bears against the front face of the main driven shaft 19, and said shaft is provided with a longitudinal rib 19^a where the lever 177 engages. Normally the jaws 172 and 173 are closed, 25 that is to say when the machine is idle the jaws are open but in operation they are closed; and the needle 140 carrying the tape 151, after passing through the box 168^a, as is shown in Fig. 16, forces its way between the said jaws which clamp the inserted end of the tape and 30 hold it while the carrier, namely the sleeves 37 and operating shaft 39 move upward together with the needle bar 134; and just after the operating shaft 39 has tripped the mechanism for raising the shear-operating tube 113^a to cut the tape, the rib 19^a on the shaft 19 will 35 engage with the trip lever 177, moving its upper end backward and thereby carrying the sliding jaw 173 in the same direction. This momentary opening of the jaws 172 and 173 permits the operator to remove the box from the table or tables 168 without danger of with- 40 drawing the inserted tape.

In the general operation of this latter form of the machine, the parts being in normal position, the shaft 19 is thrown in gear with the drive shaft 15 to receive one complete revolution. The operating shaft 39 will then 45 be carried down passing the trip lever 129 for the shear- or knife-operating mechanism without affecting it as has been stated; but as soon as the said operating shaft 39 engages the offset 136 from the needle bar slide 135, said bar and slide are carried downward, taking the 50 tape between the open shear blades 120 and 121. As the slide 135 travels downward, carrying the lower end of the needle bar 134 and its shield 137 below the shears, the collar 141 on the needle bar shield 137 will be engaged by the lip or lug 166 extending out from the front 55 bar of the frame section A', and the said lug or lip will prevent the said needle bar shield from moving further downward, as shown by dotted lines in Fig. 11, while the needle bar 134 will continue its downward travel until its needle 140 has passed the tape 151 through the 60 box 168^a and between the jaws 172 and 173, whereupon the operating shaft 39 moves upward, and the spring-controlled mechanism connected with the needle bar slide 135 draws the needle from engagement with the tape and from between the said jaws, leaving said tape 65 clamped between the jaws. Thus after the needle bar

slide 135 has reached its upper normal position shown in Fig. 13 the operating shaft 39 will trip the controlling mechanism for the shear-operating tube 113^a and will cause the shears to cut the tape, and just at that time the shaft 19 will act upon the trip lever 177 to release 70 the tape from the jaws 172 and 173, enabling the box to be removed.

The length to which the tape is to be cut is regulated by adjusting the sliding head block 111^a upward or downward as in the other form of the machine the same 75 result is accomplished by adjusting the trip sleeve 66 upon its support.

A forwardly-extending finger arm 180 is adjustably secured to the cross bar 167, against which finger arm an end of the box 168^a is pressed, so that the needle or 80 needles will enter the boxes at the same place at each operation, or at any place that may be selected. A guide block 181 is secured to a side edge of a table 168 to enable the operator to quickly direct the box to a proper position over the jaws 172 and 173. 85

Although I have denominated the elements that pass the tape through the box as needles, they are not actually needles inasmuch as the tape is simply engaged by them, therefore they may be more properly denominated in a general sense as pushing or introductory 90 members or elements, and their carriers instead of needle bars as plunger bars. I desire it to be understood that any form of rest may be employed for the boxes or other articles to which the tape is to be applied, and that the tape can be introduced at any desired point 95 singly or in multiple; and further that I do not restrict myself to the details of construction shown and described.

Having thus described my invention, I claim as new, 100 and desire to secure by Letters Patent, —

1. In a machine for applying tape to boxes, a support, a carriage mounted for movement in said support, means for imparting movement to the carriage, a plunger and a tape introductory member operated by the carriage, means for directing tape into the path of the introductory member, 105 means for temporarily holding the tape when so directed, and means for cutting the tape while so held.

2. In a machine for applying tape to boxes, a support, a carriage mounted for movement on the support, means for imparting movement to the carriage, a plunger bar, a tape introductory member operated by said carriage, means for directing tape to the said member, a detent for the tape preventing its backward movement, a feed for the tape, and a swinging device for holding an end of the tape in the path of the said introductory member. 110

3. In a machine for applying tape to boxes, a support, a carriage having sliding movement upon said support, a drive shaft, a connection between said drive shaft and the carriage, whereby to give an up-and-down movement to said carriage at each revolution of the shaft, a stop mechanism for the shaft, acting at the finish of each revolution thereof, a plunger bar and tape introductory member operated by the carriage, means for guiding tape into the path of the said member, a detent and feed for the tape which prevents its backward movement and carries it downward, a cutting mechanism, and devices operated by the carriage, for bringing the cutting mechanism into cutting action after the downward stroke of the plunger bar. 115

4. In a machine for applying tape to boxes, a support, a carriage having sliding movement upon said support, a needle bar and needle operated by the movement of the carriage, a drive shaft, a connection between the drive shaft and the carriage whereby to give an up and down movement to the carriage at each revolution of the shaft, a stop mechanism for the shaft acting at the finish of 120 each revolution thereof, means for guiding the tape into the path of the needle, a cutting mechanism in the path of 125

- the tape, a detent for the tape that prevents its backward motion, and means operated by the carriage for opening and closing the cutters of said cutting mechanism, opening them for the passage of the needle and accompanying tape, and closing them for cutting action for such passage.
5. In a machine for placing tape on boxes, a frame, a carriage slidably mounted on the frame, a reciprocating tape carrying needle, a tension-controlled member that directs the tape to the needle, a cutting mechanism adjacent to the path of the needle including horizontally mounted pivoted blades having movement to and from each other, and devices controlled by the movement of the carriage for opening and closing the cutters, opening them for the passage of the needle and closing them for cutting after the passage of said needle, and means also controlled by the carriage for timedly operating the needle relatively to the cutting mechanism.
10. In a machine for placing tape on boxes, a frame, a carriage slidably mounted on the frame, a reciprocating tape carrying needle, a tension-controlled member that directs the tape to the needle, a cutting mechanism adjacent to the path of the needle including horizontally mounted pivoted blades having movement to and from each other, and devices controlled by the movement of the carriage for opening and closing the cutters, opening them for the passage of the needle and closing them for cutting after the passage of said needle, and means also controlled by the carriage for timedly operating the needle relatively to the cutting mechanism.
15. In a machine for placing tape on boxes, a frame, a carriage slidably mounted on the frame, a support for a box, a cutting mechanism above said support, a tape-carrying needle mounted for sliding movement past the cutters of the cutting mechanism, and devices controlled by the movement of said carriage for timedly operating the needle and the cutting mechanism, first opening the cutters of said cutting mechanism, then passing the needles by the open cutters and then causing the cutters of said cutting mechanism to close and cut the tape carried between them by said needle.
20. In a machine for placing tape on boxes, a frame, a carriage slidably mounted on the frame, a support for a box, a cutting mechanism above said support, a tape-carrying needle mounted for sliding movement past the cutters of the cutting mechanism, and devices controlled by the movement of said carriage for timedly operating the needle and the cutting mechanism, first opening the cutters of said cutting mechanism, then passing the needles by the open cutters and then causing the cutters of said cutting mechanism to close and cut the tape carried between them by said needle.
25. In a machine for placing tape on boxes, a frame, a carriage slidably mounted on the frame, a support for a box, a cutting mechanism above said support, a tape-carrying needle mounted for sliding movement past the cutters of the cutting mechanism, and devices controlled by the movement of said carriage for timedly operating the needle and the cutting mechanism, first opening the cutters of said cutting mechanism, then passing the needles by the open cutters and then causing the cutters of said cutting mechanism to close and cut the tape carried between them by said needle.
30. In a machine for placing tape on boxes, a frame, a carriage slidably mounted on the frame, a support for a box, a cutting mechanism above said support, a tape-carrying needle mounted for sliding movement past the cutters of the cutting mechanism, and devices controlled by the movement of said carriage for timedly operating the needle and the cutting mechanism, first opening the cutters of said cutting mechanism, then passing the needles by the open cutters and then causing the cutters of said cutting mechanism to close and cut the tape carried between them by said needle, a table to receive the box located below the cutting mechanism, spring-controlled jaws carried by the said table, adapted to take the tape from the needle at its downward throw after passing through the box on the table and to temporarily retain said tape, and means for opening the jaws during the upward movement of the needle.
35. In a machine for applying tape to boxes, a fixed frame, a carriage mounted to slide on the same, a driven shaft, means for timing the same, a stop for the driven shaft, acting at the end of each revolution of said shaft, connections between the driven shaft and the carriage to impart an up-and-down movement thereto at each revolution of said driven shaft, a tape-carrying needle, a reciprocating carrier therefor, a fixed cutting mechanism, the needle having movement past the cutters thereof to conduct tape thereto, and devices controlled by the carriage for timedly operating said needle and opening and closing the cutters of the cutting mechanism.
40. In a machine for applying tape to boxes, a reciprocating plunger bar and a tape introductory member, a guide for the tape and a spring directing member carried by the guide and adapted to direct the free end of the tape into the path of the descending introductory member.
45. In a machine for applying tape to boxes, a reciprocating plunger bar and a tape introductory member, a guide for the tape pivotally mounted for movement to and from the plunger bar and introductory member, a swinging directing member carried by the guide and adapted to direct the tape to the lower portion of the guide into the path of the introductory member in its descent, and means for controlling the movement of the guide by the movement of the plunger bar.
50. In a machine for applying tape to boxes, a reciprocating plunger bar and a tape introductory member, a guide for the tape operated by the movement of the plunger bar, a directing member pivotally mounted upon the said guide to swing below its lower end and direct the lower end of the tape to the descending introductory member, and a detent and flap for the tape mounted to act in conjunction with the said tape guide being carried thereby.
55. In a machine for applying tape to boxes, a reciprocating plunger bar and a tape introductory member, a guide for the tape operated by the movement of the plunger bar, a directing member pivotally mounted upon the said guide to swing below its lower end and direct the lower end of the tape to the descending introductory member, and a detent and flap for the tape mounted to act in conjunction with the said tape guide being carried thereby.
60. In a machine for applying tape to boxes, a reciprocating plunger bar and a tape introductory member, a guide for the tape pivotally mounted for movement to and from the plunger bar and introductory member, a swinging directing member carried by the guide and adapted to direct the tape to the lower portion of the guide into the path of the introductory member in its descent, and means for controlling the movement of the guide by the movement of the plunger bar.
65. In a machine for applying tape to boxes, a reciprocating plunger bar and a tape introductory member, a guide for the tape pivotally mounted for movement to and from the plunger bar and introductory member, a swinging directing member carried by the guide and adapted to direct the tape to the lower portion of the guide into the path of the introductory member in its descent, and means for controlling the movement of the guide by the movement of the plunger bar.
70. In a machine for applying tape to boxes, a reciprocating plunger bar and a tape introductory member, a guide for the tape pivotally mounted for movement to and from the plunger bar and introductory member, a swinging directing member carried by the guide and adapted to direct the tape to the lower portion of the guide into the path of the introductory member in its descent, and means for controlling the movement of the guide by the movement of the plunger bar.
75. In a machine for applying tape to boxes, a reciprocating plunger bar and a tape introductory member, a guide for the tape pivotally mounted for movement to and from the plunger bar and introductory member, a swinging directing member carried by the guide and adapted to direct the tape to the lower portion of the guide into the path of the introductory member in its descent, and means for controlling the movement of the guide by the movement of the plunger bar.
80. In a machine for applying tape to boxes, a reciprocating plunger bar and a tape introductory member, a guide for the tape pivotally mounted for movement to and from the plunger bar and introductory member, a swinging directing member carried by the guide and adapted to direct the tape to the lower portion of the guide into the path of the introductory member in its descent, and means for controlling the movement of the guide by the movement of the plunger bar.
85. In a machine for applying tape to boxes, a reciprocating plunger bar, a tape introductory member, a cutting mechanism acting in conjunction therewith, a clamping device for the lower end of the tape, having clamping action in advance of the action of the cutting mechanism, and an automatically operated release for the clamping device.
90. In a machine for applying tape to boxes, a reciprocating plunger bar, a needle bar, a tape carrying instrument attached to the needle bar, a cutting mechanism acting in conjunction with the plunger bar and needle bar, the said cutting mechanism being in the path of the tape carrying instrument, an actuating mechanism common to the plunger bar, the needle bar, and the cutting mechanism, means for timedly controlling the movement of the cutting mechanism relatively to the movements of the needle bar, a support for the box, and means for removing the tape from its carrying instrument and temporarily holding said tape.
95. In a machine for applying tape to boxes, a reciprocating plunger bar, a needle bar, a tape carrying instrument attached to the needle bar, a cutting mechanism acting in conjunction with the plunger bar and needle bar, the said cutting mechanism being in the path of the tape carrying instrument, an actuating mechanism common to the plunger bar, the needle bar, and the cutting mechanism, means for timedly controlling the movement of the cutting mechanism relatively to the movements of the needle bar, a support for the box, and means for removing the tape from its carrying instrument and temporarily holding said tape.
100. In a machine for applying tape to boxes, a reciprocating plunger bar, a needle bar, a tape carrying instrument attached to the needle bar, a cutting mechanism in the path of the needle, and an actuating mechanism common to the plunger bar, the needle bar, and the cutting mechanism, acting timedly upon each of the said factors, opening the cutters of the cutting mechanism for the passage of the needle, and closing the said cutters to sever the tape, a feed device for the tape, a clamping mechanism for the lower end of the tape when the latter has been passed through a box, and a timedly operating release for the clamping mechanism.
105. In a machine for applying tape to boxes, a reciprocating plunger bar, a needle bar, a tape carrying instrument attached to the needle bar, a cutting mechanism in the path of the needle, and an actuating mechanism common to the plunger bar, the needle bar, and the cutting mechanism, acting timedly upon each of the said factors, opening the cutters of the cutting mechanism for the passage of the needle, and closing the said cutters to sever the tape, a feed device for the tape, a clamping mechanism for the lower end of the tape when the latter has been passed through a box, and a timedly operating release for the clamping mechanism.
110. In a machine for applying tape to boxes, a reciprocating plunger bar, a needle bar, a tape carrying instrument attached to the needle bar, a cutting mechanism in the path of the needle, and an actuating mechanism common to the plunger bar, the needle bar, and the cutting mechanism, acting timedly upon each of the said factors, opening the cutters of the cutting mechanism for the passage of the needle, and closing the said cutters to sever the tape, a feed device for the tape, a clamping mechanism for the lower end of the tape when the latter has been passed through a box, and a timedly operating release for the clamping mechanism.
- In testimony whereof I have signed my name to this specification in the presence of two subscribing witnesses.
